US0D1030176S

(12) **United States Design Patent** (10) Patent No.: **US D1,030,176 S**
(45) Date of Patent: ** Jun. 4, 2024

(54) **DUST PAN**

(71) Applicant: **Robert J. Krick, Jr.**, Jacksonville, NC
(US)

(72) Inventor: **Robert J. Krick, Jr.**, Jacksonville, NC
(US)

(**) Term: **15 Years**

(21) Appl. No.: **29/857,175**

(22) Filed: **Oct. 20, 2022**

(51) LOC (14) Cl. **07-05**

(52) U.S. Cl. **D32/74**
USPC .....

(58) Field of Classification Search

USPC D30/162; D32/35, 74

CPC B65F 2210/136
